UNITED STATES PATENT OFFICE.

ISIDOR KITSEE, OF PHILADELPHIA, PENNSYLVANIA.

PRODUCING INTEGRAL MULTICOLORED SCREENS ON PHOTOGRAPHIC BLANKS.

Application filed April 27, 1921. Serial No. 464,789.

To all whom it may concern:

Be it known that I, ISIDOR KITSEE, citizen of the United States, residing at Philadelphia, in the county of Philadelphia and State of Pennsylvania, have invented certain new and useful Improvements in Producing Integral Multicolored Screens on Photographic Blanks, of which the following is a specification.

10 My invention relates to an improvement in producing integral multi-colored screens on photographic blanks.

15 My invention embraces not only the process with the aid of which a celluloid or like blank may be provided with figurations of different colors, but it also contemplates the means and method of applying these figurations in a simple and economical manner to the photographic blank. I am well aware that attempts have been made to produce multi-colored screens integral with photographic blanks. I am also aware that Letters Patents in the United States and other countries have been issued for multi-colored 20 screens, but so far no multi-colored screens integral with photographic blanks, useful for moving picture work have been made commercially, and none of the Letters Patents describe the means, so that persons 25 versed in the art can produce such screens on commercial basis.

It is one thing to state that figurations of two or more colors should be produced in required minuteness on a photographic blank, 30 but it is of far greater importance to clearly point out not only the different steps required, but also the different parts of the apparatus to be used in constructing such screens, so that persons versed in the art may 35 successfully produce the same in commercial quantities.

I will first describe the process or method, with the aid of which a multi-colored screen can be produced directly on a celluloid or 40 other suitable blank. As my invention has more special reference to moving picture films I take it for granted that the photographic blank consists of the usual celluloid film.

45 In the accompanying drawing, which illustrates one form my invention may take, Figs. 1 to 6 inclusive are plan views of parts of a film representing different stages in

the course of producing the multi-colored screens thereon. Fig. 7 is a vertical longitudinal section partly in elevation of the device used in the production of the integral color screen. Fig. 8 is a vertical transverse section taken on the line 8-8 of Fig. 7. Fig. 9 is a plan view of two adjacent discs 50 out of which the roller as illustrated in Fig. 8 is produced and of which the discs of Fig. 7 are parts. Fig. 10 is a plan view of one of the discs of Fig. 9, the part not recessed being provided with teeth. Fig. 11 is a plan 55 view of one of the discs of Fig. 9, the disc comprising a number of recessed parts interspersed by parts not recessed.

In Figs. 1 to 6, 1 is the celluloid base, 2 the color with which one surface of the celluloid is tinted, and as I have selected here the screen to consist of the two colors, green and red, the color 2 represents here, green. 3 indicates a covering layer, surfacing the green tinted celluloid. 4 indicates the spaces 60 from which the covering layer and the green tint have been removed. 5 indicates the formerly clear spaces tinted now with a second color, here red. In Fig. 6 the whole screen is indicated by 6 and consists here of 65 red lines interspersed by green lines, the covering layer being entirely removed. It will be noted that the lines—red as well as green—do not extend the entire length of the film, but that the lines, the red as well as the 70 green are broken up and interspersed longitudinally as well as transversely, the red and the green lines alternating each other in both directions. These alternations are produced through special arrangement of the 75 discs as will later on, in describing these 80 discs, be more clearly set forth.

In Figs. 7 and 8 the device consists of a race-track 8, in its broad construction similar to the construction of the race-track in 85 moving picture projectors and provided with means 9-9 to adjust the same, so that the film passing through the race-track may be provided with the required pressure to hold the same in level position. 10 indicates a 90 series of discs comprising the discs 11 and the discs 12, the discs 12 being positioned alternately between the discs 11. Each of the discs, 11 as well as 12, is so constructed 95 that only part of same, here one-half of its circumference will in the working of the 100

device come in cutting contact with the underlying film and for this reason each of the discs comprises the cutout part of clearance 24, designed not to contact with the film and 5 the part indicated by 25, which in the working of the device comes in cutting contact with the film, whereby it will remove that part of the substratum and color layer with which the film is provided, but it has to be 10 noted, that in the assembled roller the discs are assembled in a manner, so that the cutout part of one disc is opposite to the cutout part of the adjacent disc. In other words, when the discs are assembled on the 15 shaft they will form or present a roller consisting of a series of discs, one-half of the circumference of each disc recessed, but the recessed halves of the adjoining discs oppositely positioned, as is clearly illustrated 20 in Fig. 9, so that in the working of the device, that is during each revolution of the roller, only one-half of the discs will be active as cutting discs during one-half of the revolution of the roller and the other 25 half of the discs will only be active as cutting discs during the second half of the revolution. The whole series of discs is positioned on and keyed to the revolvable shaft 13. 14—14 are means to hold the discs together 30 in tight assembly. 15 are the means to raise and lower and place in exact relation the whole series of discs as to the film 16 passing through the race-track. In practice, I have found that the multi-colored screen does 35 not need to have colored lines thereon of a smaller width than about 1-500 of an inch for each line. The screen therefore will consist here of green lines of about 1.500 of an inch in width interspaced, transversely as 40 well as longitudinally, by red lines approximately the same width. Taking now for granted that the screen will consist, transversely considered of 500 lines per inch, 250 of each color, and taking for granted that the 45 screen will be produced with the aid of the device as illustrated in Figs. 7 and 8, it has to be stated, that each of the discs, 11 as well as 12 should be about 1-500 of an inch in thickness. For better understanding I call 50 the whole series of discs, as assembled on the shaft, the cutting roller and each inch of this cutting roller will therefore consist of 500 discs, 250 of which are recessed as to one half of their circumference in respect 55 to one position of the roller and 250 of which are recessed as to one half of their circumference in respect to the opposite position of the roller. In practice, I have found that a very convenient size for these discs is from 60 2 to 3 inches in diameter. 17 is an adjustable freely revolving roller, positioned in the cutout place 26 of the race-track and adapted to contact with the film 16, so that the same may not deviate from its proper position. 18 is an 65 electric motor, with the aid of which the

cutting roller may be revolved. I have here shown the motor as being connected to the shaft 13 with the aid of a belt 27. The reason for this is: if the motor be connected directly to the shaft, the vibrations of the 70 motor may injuriously affect the operation of the cutting roller. 19 is a spool from which the film is unwound during operation, 20 the film already acted upon by the cutting roller and 21 is the means to draw the film 75 under the cutting roller.

The mode or method of producing the multi-colored screen according to my invention is substantially as follows: As my invention has more special reference to moving picture films, I will refer to the celluloid blank as film or part of film, useful to take thereon, after completion of the process and proper coating with pan-chromatic emulsion, negatives with the aid of which, 80 positives may be produced and exhibited in the same manner and with substantially the same apparatus as moving pictures are projected today.

The first requisite is, a celluloid blank in 90 the form of a film, either perforated or unperforated. This film is then tinted on one surface with one color. The tinting with the color may be produced with the aid of rollers or brushes, and in this case, 95 the opposite surface does not require any protective coating. The dye-solution should be such as to affect the celluloid proper, but in a very mild degree. For this purpose dyes have to be selected, soluble in 100 alcohol, and an agent affecting the celluloid has to be added. This agent may consist of any of the usual solvents, such for instance as amylacetate, acetone or ether. In 105 the practical working, it was found, that a very even tint can be applied to the celluloid, if the film is immersed in the liquid and moved too and fro. But in this case the underside or opposite surface has to be 110 protected from the action of the dye solution. This can readily be accomplished by covering the underside with a light coating of gelatine or gum arabic. Care shall be taken not to make the dye solution too active or to leave the film too long in this 115 solution, as otherwise the tinting will penetrate to a depth greater than desired. After the film is taken from the color bath, the same is subjected to a drying process either 120 with or without the aid of artificial means. When completely dry, the tinted surface is provided with a protecting layer, such for instance as was used for protecting the underside from the dye solution, that is 125 with a coating of gelatine, gum arabic or substance similar in action. After drying the film is subjected to a cutting process with the aid of the device, substantially as is illustrated in Figs. 7, 8 and 9, in the following manner: The film is wound around 130

a spool and the free end of the film is threaded or carried through the race-track of the device and this end is then carried through the pulling means, here 21. This means is adapted to be rotated with the aid of an electric motor or device similar in action. In practice I prefer an electric motor as its speed can easily be regulated with the aid of a variable rheostat. The cutting 10 roller has to be adjusted then in a manner so that the discs at the true or unrecessed diameter should slightly press on the film and should, when rotated cut through the protecting layer and that part of the surface of the film which is tinted, so that the protective layer as well as the tinted surface is removed and a space freed from the color and protective coating (substratum) is produced. In practice it has been found that the greater the rotating speed of the cutting roller, the greater the efficiency of same and for all practical purposes it is suggested, that the speed of the cutting roller should be about double or greater than the speed of the moving film. 1,800 to 2,500 revolutions per minute of the cutting roller is not excessive. This speed can be regulated by the sizes of the pulleys on the shaft of the cutting roller and on the shaft of the motor respectively. The movement of the film should be in a direction opposite to the direction of the revolving cutting roller, as is clearly indicated by the different arrows; the feathered arrow indicating the direction of rotation of the cutting roller and the unfeathered arrow the direction of the movement of the film through the race-track. After the whole length of the film has passed through the race-track and has been acted upon by the cutting roller, it will present an appearance substantially as follows: Colored lines of comparatively short length interspaced transversely and longitudinally by short lines minus the color and the protective layer. In other words the film will represent a surface in which short colored lines will alternate transversely and longitudinally with short clear lines. A film of this description is clearly illustrated in Fig. 4.

The upper surface of the film so produced is then subjected to a dye solution of a color different from that of the first dye solution, but this solution should have substantially the same properties as the first dye solution. It should effectually tint the celluloid now laid bare through the cutting off of the protective layer and formerly tinted part of the celluloid. It has to be stated, that if the laying on of the second color is produced with the aid of rollers or brushes, it is unnecessary to give the underside a protective coating; but, as it has been found in practice, that the immersion of the whole film in the dye solution is the more practical and efficient, then the underside has to be provided with a protective layer similar to the substratum or protective layer above referred to. Care has to be taken that the individual cutters or discs should be of exactly the same diameter, so that no disc should protrude or be recessed as compared with the other discs, as otherwise the finished product will not be satisfactory. Care should also be taken to place the cutting 75 roller in exact position as to the surface of the film to be cut and therefore the adjustment as indicated by 15 in Figs. 7 and 8 should be micrometrically correct. The film, after the second tinting will, if green 80 and red are used as dyeing solutions, represent a surface substantially as illustrated in Fig. 5. The remaining protective coating may then be removed by simply washing the film in water and the film will present a surface substantially as illustrated in Fig. 6.

To reduce the heat, generated through the friction of the cutting roller and the moving film, means have to be provided to conduct this heat from the device and a blast of cool air, as practice has proven, will effectually reduce the temperature of the cutting roller as well as that of the film. In Fig. 7, 23 indicates part of the means through which the cold air is conveyed onto the cutting 85 roller and the moving film.

In the drawing I have selected to be shown a perforated film as being acted upon by the cutting roller, and therefore the means to draw the film through the race-track is illustrated as the usual sprocket wheels, but if the film be unperforated, suitable friction rollers may be substituted for the sprocket wheels.

During the explanation of the drawing I have given figures of the diameter of the discs, but it is obvious that the diameter of these discs maybe increased or decreased in accordance with requirements. I have also pointed out satisfactory speeds of the cutting roller as well as of the moving film; these speeds may be increased or decreased or the relative speeds of the roller and of the film may be changed in accordance with requirements without departing from the 100 scope of my invention.

I have illustrated the discs to be smooth-edged because I have found this construction of the disc very satisfactory, but if it is desired to make the edges ragged, notched or toothed, results may also be produced from the revolving roller, but care has to be taken that the ragged edges or teeth 28 should not be clogged up or when clogged up, that they be cleaned as otherwise the result will not be satisfactory and the film will present an uneven appearance. I must also add, that if toothed discs be employed, the movement of the film as to the number of revolutions of the discs should be greatly 105 110 115 120 125 130

4
reduced. I have also illustrated and described each cutting disc to comprise one continuous cutting edge, interspaced by one continuous recessed space, but it is obvious
5 that each of the discs may comprise a series of shorter cutting edges, interspaced each by a recessed space.

The attention of persons desiring to practice my invention has to be called to the
10 fact that the length of each of the colored lines will depend to the greatest extent on the ratio of speed between the revolving discs and the moving film. The greater the difference of speed between the two elements
15 that is the greater the speed of the revolving roller and the slower the speed of the moving film in relation therewith, the shorter will be the transparent lines produced by the cutting of the discs and therefore the shorter
20 will be the colored figurations in the finished film.

Having now described my invention, what I claim as new and desire to secure by Letters Patent is:

25 1. The method of producing multi-colored screens on blanks useful for photographic purposes which consists in tinting one surface of a celluloid blank with one color, protecting the tinted surface with a protective coating, removing the protective coating and tinted surface longitudinally from alternate areas of the tinted blank and tinting the freed parts with a second color.
30 2. In the process of producing multi-colored screens on celluloid blanks the steps which consists in first tinting one surface with one color and then removing longitudinally considered alternate areas of said surface.
35 3. The method of producing multi-colored screens integral with moving picture films which consists in first providing one surface of a celluloid blank with a protective coating, immersing then said blank in a dye-solution adapted to attack the unprotected surface in a manner, so as to tint the same, coating the tinted surface when dry with a protective layer, clearing longitudinally considered alternate areas of the tinted surface from its protective layer and tint, immersing the blank in a second dye solution different in color from the first dye solution, and adapted to tint the free parts with a second color and then removing the protective layer entirely.
45 4. In the process of producing multi-colored screens integral with photographic blanks the improvement which consists in causing a series of cleared short lines to be produced on a celluloid film tinted on one surface with a required color, the cleared short lines alternating with short colored lines.
50 5. The process of producing an integral screen on moving picture films, which con-

sists in cutting short lines into the previously tinted surface of a celluloid film in a manner, so as to remove the tint from said lines and then tinting the lines from which the color has been removed, with a
70 second color.

6. In the art of producing integral color screens on blanks useful for photography the improvement which consists in causing to be produced through the mono-tinted surface of a blank through the removal of parts of said blank to a predetermined depth longitudinal unconnected areas in intaglio and then tinting said areas with a different color.
75

7. The art of producing color screens on blanks useful for photography which consists in clearing longitudinally considered unconnected and alternate areas through the previously tinted surface of a blank, and then tinting said cleared areas with a
85 different color.

8. In the art of producing integral screens for moving picture films the steps as follows: removing longitudinally considered short lines of the protective coating and tint of a previously tinted and coated celluloid film and then selectively tinting the freed parts with a color differing from the first tint.
90

9. In the art of producing integral color screens for blanks useful for photography the step which consists in first removing longitudinal and unconnected parts of the previously tinted surface and then tinting the freed parts with a different tint.
95

10. In the art of producing integral color screens on celluloid blanks useful for photography the improvement which consists in causing to be produced through the previously tinted surface of a blank at one and the same operation, longitudinally as well as transversely considered, series of short and unconnected clear lines in intaglio and later tinting these lines with a color differing from the first tint.
105

11. In the art of producing color screens useful for photographic purposes the method which consists in causing to be produced through the previously tinted surface of a blank short unconnected areas free from said tint through the removal of the tinted surface, interspaced by short areas retaining their previous tint.
115

12. In the art of producing color screens on blanks useful for photographic purposes the step which consists in causing to be produced through the previously tinted surface of a blank short unconnected areas free from said tint, interspaced by short areas retaining their previous tint.
120

13. In the art of producing integral color screens on moving picture films consisting of short lines of one color interspaced by short lines of a second color, the method which consists in first coloring the surface
125

of a blank with one color, applying a protective coating to said colored surface, removing the coating and tint from alternate areas, tinting said areas with a second color and removing then the protective coating from all areas.

14. In the art of producing multi-colored

screens on photographic blanks useful for photography the step which consists in removing simultaneously from the surface 10 of a celluloid blank a series of lineal areas interspaced longitudinally and transversely.

In testimony whereof I affix my signature.
ISIDOR KITSEE.
